UNITED STATES PATENT OFFICE.

MARY ELIZABETH SMITH, OF ORLANDO, FLORIDA.

FOUNTAIN-COMB.

1,180,199.

Specification of Letters Patent. Patented Apr. 18, 1916.

Application filed March 16, 1915. Serial No. 15,305.

To all whom it may concern:

Be it known that I, MARY ELIZABETH SMITH, a citizen of the United States, residing at Orlando, in the county of Orange and State of Florida, have invented certain new and useful Improvements in Fountain-Combs; and I do declare the following to be a full, clear, and exact description of the invention, such as will enable others skilled 10 in the art to which it appertains to make and use the same.

My invention relates broadly to improvements in toilet articles, and more particularly to fountain combs and the like for 15 applying tonics and dyes to the hair.

Heretofore, it has been the common practice to apply hair tonics and dyes with the tips of the fingers, massaging the scalp in an endeavor to equally distribute the fluid. 20 It has been found, however, that by this method the fluid cannot be evenly distributed, and if dye is used, the fingers of the person applying the same are noticeably stained. This is of course very undesirable, since days and even weeks are often required before the stains may be removed from the hands. In order to overcome this difficulty, numerous fountain combs have been placed upon the market, but such 25 devices have, up to the present date, met with little success, since they either do not allow sufficient fluid to be discharged, or else so much of this fluid is delivered, that it runs from the scalp of the user, thus often soiling her face as well as her clothing.

It is the object of my invention, therefore, to provide a fluid applying device which is so constructed as to allow exactly the proper amount of tonic or dye to be discharged, this amount being totally under 40 control of the person using the same. In accomplishing this end, I provide certain novel features of construction and combination hereinafter described and particularly 45 pointed out in the claim.

In describing the invention, I shall refer to the accompanying drawings, wherein like reference characters designate corresponding parts throughout the various views, and 50 wherein:

Figure 1 is a side elevation of the invention partly in section; Fig. 2 is an end view thereof, and Fig. 3 is a vertical transverse section as seen along the plane indicated by 55 the line 3-3 of Fig. 1.

In this drawing, constituting a part of the

application, the numeral 1 designates a fluid receptacle which is here shown in the form of an elongated comparatively flat casing, the lower side of the latter being provided with a plurality of perforations 2 from which a series of fluid-distributing members 3 project. In the present case, the members 3 are shown in the form of comb teeth, although it will be evident that were 65 the receptacle 1 in the form of a brush back, rather than the back of a comb, the distributing members 3 could well be in the form of bristles. In employing comb teeth, however, the same are provided with longitudinal ports 4 which lead from the discharge openings 2 through the ends of the teeth, branch ports 5 being also provided. In most cases, these ports 5 lead from the main ports 4 through the sides of the teeth, 75 as clearly shown in Figs. 1 and 3.

The receptacle 1 is shown in the accompanying drawing as having a lid 6 which, when closed, is disposed in fluid-tight contact with the open upper side of said receptacle, whereby to prevent the escape of fluid placed therein. Although any preferred type of hinge could be provided for connecting one edge of the lid 6 to one edge of the receptacle 1, these hinges are preferably in 85 the form of elastic straps 7, and an elastic loop or the like 8 is secured to the opposite edge of the lid 6 to be stretched and passed over the headed stud 9 which projects laterally from the receptacle 1. By constructing 90 the hinges 7 and the latch 8 of elastic material, it will be evident that the lid 6 will be drawn into fluid-tight contact with the upper side of the receptacle 1.

Disposed within the receptacle 1, is an 95 absorbent member 10 which, in the present case, is considered as being a sponge, although it will be evident that felt or any material capable of absorbing liquids by capillary attraction, could well be used. 100 Likewise disposed in the receptacle 1 and contacting with the absorbent member 10, is a manually operable inwardly movable presser-bar 11 which gradually decreases in width from its upper to its lower edge. By 105 so constructing the presser bar 11, it will exert a wedging action on the absorbent member 10 as shown in Fig. 3, thus forcing such member into frictional contact with the sides of the cavity in the comb back when 110 said bar is forced inwardly. The result is that the member 10 is prevented from being

forced bodily inward to such an extent as to obstruct the passage of fluid through the ports 2.

In the type of the invention shown in the drawing, the bar 11 is provided with an operating member including a stem 12 which projects slidably through an opening in the lid 6, and a knob or the like 13 which is secured upon the outer end of said stem. 10 By this construction, it will be evident that the user of the comb may force inwardly upon the knob 13 when it is necessary to discharge more fluid into the hair, whereupon the absorbent member 10 will be compressed by the presser-bar 11, and such fluid will be discharged through the outlet openings 2 and through the ports 4 and 5. It will be understood, however, that the member 10 must have previously been saturated 15 with the tonic, dye, or other fluid to be applied to the hair and scalp.

In the foregoing, I have described certain specific details of construction for reducing the invention to an operative device, and in the drawing, have shown such details, but it will be obvious that I need not be limited thereto otherwise than as specified in the following which I claim as my invention:

A fountain comb comprising a back hav-

ing therein an elongated cavity opening 30 through its upper edge, a plurality of comb teeth depending from said back and having ports leading from the cavity to their exterior, a cover plate resting on the comb back and having a central opening, an upright stem extending through such opening and having a knob on its upper end, an absorbent member in the cavity, and a horizontally disposed presser bar carried by the lower end of the stem and positioned between the absorbent member and the cover plate, said bar being spaced from the sides of the cavity and being gradually decreased in width from its upper to its lower edge, whereby to exert a wedging action on the 40 absorbent member and to thus force the same into frictional contact with the aforesaid sides of the cavity, thereby preventing inward movement of said bar from moving the absorbent member inwardly to such an 45 extent as to close the ports.

In testimony whereof I have hereunto set my hand in presence of two subscribing witnesses.

MARY ELIZABETH SMITH.
